Filed Oct. 22, 1965, Ser. No. 87,751

Term of patent 14 years

(Cl. D26—1)

The figure is a front perspective view of a timing device, showing my new design. The rear, bottom, left side, and top of the timing device are substantially flat and unornamented.

The essential features of the design reside in the full line portions thereof.

I claim:

The ornamental design for a timing device or similar article, substantially as shown and described.
